Fig. 4.

Fig. 5.

FIGURE 1 is a plan view of a plastic sheet material showing my new design wherein the design unit is repeated in regular succession as indicated by the extensions beyond the unit boundaries;

FIGURE 2 is a plan view of another embodiment of my design wherein the design unit is alternately inverted vertically and matched horizontally as indicated by the extensions beyond the unit boundaries;

FIGURE 3 is a plan view of a third embodiment of my design wherein the design unit is alternately inverted both vertically and horizontally as indicated by the extensions beyond the unit boundaries;

FIGURE 4 is a fourth embodiment of my design wherein the design unit is successively set at right angles about an axis defined by each corner of each design unit as indicated by the extensions beyond the unit boundaries; and

FIGURE 5 is an enlarged plan view of the design unit, which constitutes the essential feature of my new design.

I claim:

The ornamental design for a plastic sheet material or the like, substantially as shown and described.
